[57] CLAIM

The ornamental design for a soil erosion prevention block, as shown and described.

DESCRIPTION

FIG. 1 is a perspective view of a soil erosion prevention block showing my new design as seen from the top; FIG. 2 is a perspective view thereof as seen from the bottom;

FIG. 3 is a top perspective view of a second embodiment of a soil erosion prevention block;

FIG. 4 is a bottom perspective view thereof;

FIG. 5 is a top perspective view of a third embodiment of a soil erosion prevention block;

FIG. 6 is a bottom perspective view thereof;

FIG. 7 is a top perspective view of a fourth embodiment of a soil erosion prevention block;

FIG. 8 is a bottom perspective view thereof;

FIG. 9 is a top perspective view of a fifth embodiment of a soil erosion prevention block;

FIG. 10 is a bottom perspective view thereof;

FIG. 11 is a top perspective view of a sixth embodiment of a soil erosion prevention block; and,

FIG. 12 is a bottom perspective view thereof.
